US00D940702S

(12) **United States Design Patent** (10) **Patent No.:** **US D940,702 S**
(45) **Date of Patent:** **** Jan. 11, 2022**

(54) **PORTABLE ELECTRONIC DEVICE**

(71) Applicants: **Richard Cartledge**, West Palm Beach, FL (US); **Ami Brannon**, West Palm Beach, FL (US); **Kermit Falk**, West Palm Beach, FL (US); **Peter Kratsch**, West Palm Beach, FL (US); **Vincent Manopoli**, West Palm Beach, FL (US)

(72) Inventors: **Richard Cartledge**, West Palm Beach, FL (US); **Ami Brannon**, West Palm Beach, FL (US); **Kermit Falk**, West Palm Beach, FL (US); **Peter Kratsch**, West Palm Beach, FL (US); **Vincent Manopoli**, West Palm Beach, FL (US)

(73) Assignee: **NEUVANA, LLC**, West Palm Beach, FL (US)

(**) Term: **15 Years**

(21) Appl. No.: **29/716,474**

(22) Filed: **Dec. 10, 2019**

(51) LOC (13) Cl. **28-03**

(52) U.S. Cl.

USPC **D14/341**; D24/200

(58) **Field of Classification Search**

USPC ..... (57) **CLAIM**

The ornamental design for a portable electronic device, substantially as shown and described.

DESCRIPTION

FIG. 1 is a top front perspective view of our new design; FIG. 2 is a bottom front perspective view of the design of FIG. 1;

FIG. 3 is a front elevational view of the design of FIG. 1;

FIG. 4 is a rear elevational view of the design of FIG. 1;

FIG. 5 is a left side elevational view of the design of FIG. 1;

FIG. 6 is a right side elevational view of the design of FIG. 1;

FIG. 7 is a top view of the design of FIG. 1; and,

FIG. 8 is a bottom view of the design of FIG. 1.

1 Claim, 6 Drawing Sheets
